UNITED STATES PATENT OFFICE.

WILLIAM J. MURRAY, OF MAMARONECK, NEW YORK.

SCAFFOLD.

Application filed November 15, 1921. Serial No. 515,944.

To all whom it may concern:

Be it known that I, WILLIAM J. MURRAY, a citizen of the United States, and a resident of Mamaroneck, in the county of West-
5 chester and State of New York, have invented a new and Improved Scaffold, of which the following is a description.

My invention relates to scaffolds adapted to be suspended on a building to be raised 10 or lowered as desired.

The general object of my invention is to provide a novel raising and lowering means of simple construction adapted to wind in and pay out the suspending ropes or cables 15 in the raising and lowering of the scaffold, the invention having in view especially to promote convenience in the operation of raising and lowering the scaffold and to insure safety and positively and automatically 20 preventing the accidental dropping of the scaffold at one or both ends.

The nature of the invention and its distinctive features and advantages will more clearly appear as the description proceeds.

Reference is to be had to the accompanying drawings forming a part of this specification, it being understood that the drawings are merely illustrative of one example 25 of the invention.

30 Figure 1 is a front elevation of a scaffold suspended from the roof;

Figure 2 is an enlarged side elevation of the raising and lowering means, the scaffold proper being in transverse vertical section;

35 Figure 3 is an elevation at right angles to Figure 2;

Figure 4 is a detail in vertical section adjacent to one end of the drum operating shaft.

40 In carrying out my invention in practice the platform 10 of the scaffold may be of any approved form, here shown as comprising a ladder 11 having planks laid on the ladder rungs 12. The platform 10 rests in 45 hanger stirrups 13 secured at their upper ends by bolts 14 to the parallel terminals 15 on the frames 16 of the hoisting and lowering units.

As the two hoisting and lowering units 50 of the scaffold are alike, it will suffice to describe one. Each hanger stirrup 13 is formed from strip metal the sides of which are upwardly convergent and the upper terminals of which are parallel and receive a transverse bolt 17 having a lever nut 18 for

tightly clamping the sides of the hanger against the bolts 14 which lie above and below the bolt 17 at right angles thereto.

The suspension cables 19 are here shown as having hooks 20 at their upper ends to hook over a cornice A. It will be understood that any expedient may be adopted for fastening the upper ends of the suspension cables. Each cable 19 runs over an idler sheave 21 on a shaft or tie rod 22 at the upper end of the frame 16 and from said sheave to a winding drum 23, the shaft 24 of which is turnably mounted in said frame 16. On the drum shaft 24 is a gear wheel 25 over which advantageously a housing 26 may be provided on frame 16. The gear wheel 25 meshes with a drive pinion 27 on a counter shaft 28 having bearings in the frame 16, said drive shaft 28 having a crank handle 29. The drive pinion 27 is fast on the shaft 28 and said shaft is adapted to have axial movement in the frame 16 in addition to its turning movement whereby an axial movement of the shaft will shift the pinion 27 thereof into or out of engagement with a clutch 32 fixedly secured by rivets 33 or the like to the frame 16, said clutch and said pinion 27 having mating clutch teeth 31.

A compression spring 30 is coiled about the shaft 28 at a side of the frame opposite the clutch 32, the said spring abutting at one end against the frame and abutting at its other end against the collar 30^a on the shaft 28 so that the spring tends to maintain the shaft in position with the pinion 27 engaging the clutch 32 to prevent turning of the shaft 28 and thereby preventing turning of the drum 23.

Turning with the drum shaft 24 is a ratchet wheel 34 engaged by a pawl 35 for preventing retrograde movement. Thus, the pawl 35 will hold the drum against turning after the pinion 27 is released from the clutch 32, but will slip over the ratchet 34 in the turning of the drum in response to the turning of the drive shaft 28 and pinion 27.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A hoisting and lowering unit for the suspension cables of scaffolds, said unit comprising a frame, a drum in said frame, a gear wheel rigid with said drum, a drive shaft turnable and slidably axially of the frame, a pinion on said shaft meshing with said gear wheel, a fixed clutch on said frame coaxial with the drive shaft, said clutch and pinion having mating clutch teeth, and spring means acting on said shaft and tend-
- ing to maintain said pinion in engagement with said clutch.
2. In a windlass of the character described, a frame, a drum revolvably carried by said frame, a driven gear on said drum, a drive shaft carrying a pinion meshing with said gear revolvable and movable axially in said frame, and fixed clutch members on said frame engageable and disengageable by said pinion by an axial movement of the drive shaft.

WILLIAM J. MURRAY.
